UNITED STATES PATENT OFFICE.

WARREN NOBLE, OF CLEVELAND, OHIO, ASSIGNOR TO THE FRANTZ PREMIER COMPANY, OF CLEVELAND, OHIO, A CORPORATION OF OHIO.

DESIGN FOR A CASING AND STAND FOR ELECTRIC FANS.

48,570.

Specification for Design.

Patented Feb. 15, 1916.

Application filed October 18, 1915. Serial No. 56,620. Term of patent 14 years.

To all whom it may concern:

Be it known that I, **WARREN NOBLE**, a subject of the King of Great Britain, residing at Cleveland, in the county of Cuyahoga and State of Ohio, have invented a new, original, and ornamental Design for a Casing and Stand for Electric Fans, of which the following is a specification, reference being had to the accompanying drawing, forming part hereof, wherein—

Figure 1 is a perspective view and Fig. 2 is a side elevation of an electric fan exhibiting my new design.

I claim:—

The ornamental design for casing and stand for electric fans as shown.

WARREN NOBLE.
